Hugo G. Modine, Chicago, Ill., assignor to
 Otarion, Inc., Chicago, Ill., a corporation of
 Illinois

Application April 4, 1940, Serial No. 327,788

9 Claims. (Cl. 179—107)

The present invention relates to hearing aids and more particularly to receivers or ear pieces for hearing aids.

The primary object of the invention is the provision of an ear piece which is small in size and light in weight and which is adapted to use a twister type of crystal for the purpose of actuating the diaphragm.

A further object of the invention is the provision of a convenient means for attaching wires to the various parts of hearing aids so that they may be conveniently removed and replaced and at the same time assure positive contact.

A still further object of the invention is the provision of an ear piece actuated by a crystal in which the response is over a greater frequency range than has generally been available in devices of this kind and size.

A still further object of the invention is the provision of special means for mounting the crystal and the driving mechanism for connecting the crystal to the diaphragm which permits of better response than has been available in devices of this kind in the past.

A still further object of the invention is the provision of devices of the class described which are simple, light in weight, efficient and conveniently shaped.

In the drawing the device and its various parts have been shown on an enlarged scale so as to make them more readily understandable. In actual production the device is made of such size as to conveniently fit the ear. It is to be understood, of course, that the drawing is purely illustrative and modifications may be made in the structure and arrangement of the parts and the type of parts used without departing from the true spirit and scope of the invention as it has been defined by the appended claims.

Referring to the drawing:

Fig. 1 is a top plan view with the interior of the mechanism shown in dotted lines;

Fig. 2 is a view showing a portion of the device that fits adjacent the ear;

Fig. 3 is a perspective view showing in detail the mounting for the crystal and the driving connection which is employed to drive the diaphragm;

Fig. 4 is a view in cross section showing the interior of the mechanism;

Fig. 5 is a sectional view taken on the line 5—5 of Fig. 4;

Fig. 6 is a sectional view taken on the line 6—6 of Fig. 4;

Fig. 7 is a sectional view taken on the line 55

7—7 of Fig. 4 showing in detail the means for connecting the wires to the ear piece; and

Fig. 8 is a section taken on the line 8—8 of Fig. 7.

5 The device consists generally of a casing or housing 11 which is generally circular in shape as indicated in Figs. 1 and 2 except that at its base it has an offset portion 12, the purpose of which will be hereinafter described.

In order to close the housing a screw threaded cap member 13 is provided having a central orifice 14. Mounted within the housing is a diaphragm 15, the diaphragm being preferably mounted between spacer rings 16 and 17 as shown in section in Fig. 4.

20 The diaphragm is driven by a twister type of crystal element, the crystal element being indicated by the reference character 18. The crystal element, being square in shape, sets very nicely into the offset portion of the housing so that the driving point of the crystal element is directly beneath the center of the diaphragm 15.

The diaphragm is connected to the crystal by a wire provided with several loops which are spaced apart a distance equal to the thickness of the crystal. The loops which are indicated by the reference characters 19 and 20 respectively are bent towards each other so as to engage the crystal element and to act as a driving means for the diaphragm 15. The wire forming the loops 19 and 20 extends through a small opening in the diaphragm and is sealed to the diaphragm by any suitable sealing compound indicated at 21.

35 The mounting for the crystal element in the receiver is of very great importance as I have found that depending upon the type of mounting employed the response of the device is controlled to a large extent. For the purpose of mounting the crystal I have found that the back corner 22 of the crystal which fits into the projecting portion 12 must be provided with a certain amount of rigidity and at the same time permit the crystal to yield in order to secure the best frequency response.

40 A preferred example of mounting consists in using a material which is resilient but which returns to its normal position rather slowly. The material I have found particularly desirable for the mounting is soft composition pyrolite No. 2450 manufactured by E. I. du Pont de Nemours and Co. and which has been known as Viscolloid No. 7775-60. This material is a highly plasticized cellulose nitrate plastic especially designed for damping applications. This material is cut into 50 a square which is substantially smaller than the

area of the crystal and is mounted at the corner 22 of the crystal. In order to give a certain amount of rigidity but still permit free actuation of the crystal I have provided around the corner 22 of the crystal and the mounting member 23 a stiffening member which is L-shaped indicated by the reference character 23a. This stiffening member is preferably about 5-thousandths of an inch thick and I have found a suitable material for making such stiffening member is cellulose acetate. However, my tests have shown that other stiffening members than cellulose acetate may be employed but it is highly desirable to provide a stiffening member of certain amount of rigidity at this point of relatively thin material.

The forward leg of the crystal 24 is not supported by any mounting means as it is this leg which actuates the driving member for the diaphragm and it is preferable that it be free to vibrate in response to electrical actuation of the crystal. The corners 25 and 26 of the crystal, or what I prefer to call the side legs of the crystal, have mounting members thereof 27 and 28 which consist of material the same as that used at the back leg 23 but without any stiffening means.

In addition to the material referred to above I have also found that certain grades of cork may be employed as cork seems to have resilience but at the same time relatively slow response. However, cork is not as satisfactory as Viscolloid because of its non-uniformity but I refer to it to designate generally the class of materials which are capable of functioning as mounting means.

The mounting legs 27 and 28 are preferably of much smaller area than the mounting leg 23 as I have found the best response is given when these legs are relatively smaller than the leg 23.

A crystal which I have employed satisfactorily is approximately $\frac{3}{8}$ of an inch square and provided with a rear supporting leg approximately $\frac{3}{16}$ of an inch square and side legs approximately $\frac{1}{16}$ of an inch square. The thickness of these legs is found to be most satisfactorily when they are $\frac{1}{16}$ of an inch thick. This particular proportion appears to give optimum response. It is obvious that the proportion and size of the parts would be varied somewhat with crystals of different size.

The area of the supports and the thickness of the supports definitely affects the responsiveness of the crystal as well as does the type of material employed in constructing the supports. Having pointed out the essential characteristics to be considered, it will be apparent that with the employment of different types of materials and different sizes of crystals that with very small experimentation the optimum areas for the supporting legs and the thickness can readily be determined by generally following the proportions indicated.

At the opposite side of the case or housing from which is mounted the crystal I provide a pair of contacts 29 and 30 to which the leads 31 and 32 of the crystal extend. These contacts, as is shown in Fig. 4, extend through the casing and are provided with an enlarged projecting head 33 to which the connecting member shown in Fig. 7 may be readily applied.

The connector 37 consists of a small casing 38 which is provided with a laterally projecting head 39. Mounted in the head 39 is an insulating member 40 which is provided with keyhole shaped slots 41, the enlarged portion of which is adapted to pass over the head 33. In back of the slots 41

are contacting spring members 42 which bear toward the insulating member 40 so that when the contact members 29 are slipped into the key-hole shaped slots 41 the spring members 42 bear against the head member 33 and form tight wiping contacts. Furthermore, the keyhole shaped slots have the effect of locking the connecting member onto the housing 11. The housing 11 is preferably provided with a depressed portion 43 shaped as shown in Fig. 1 to receive the connecting member. The employment of a twisted type of crystal element which can be partially mounted in the projection in the bottom of the case with its driving point at the center of the case permits depression of the case at the top to provide space for the connecting element. This is a feature of considerable importance in obtaining compactness.

Attached to the contacting springs 42 is a pair 20 of lead wires which are brought together in a common flexible sheath or cable 44. The sheath 44 tends to hold the wires together and prevent them from being pulled out at the connections. Furthermore, being flexible, the end which projects beyond the casing member prevents a short 25 turn or twist being made in the lead wires at that point, thereby preventing breakage of the lead wires.

It is to be noted that the design of the case is 30 such that it permits the employment of a twister type of crystal element, which element gives greater driving force than the bender type of crystal which is normally employed in devices of this kind and due to the projection 12 the diameter of the case may be kept at a minimum but still adequate room is provided for all the mechanism. The device is very light and will fit very nicely into the ear, the projection or tapered portion of the case 12 fitting adjacent the tragus 35 portions of the ear.

I have found that a device constructed in accordance with my invention has a more nearly level frequency response over a wider frequency range than has been obtained in devices heretofore constructed for this purpose. Furthermore, due to the particular casing construction I have discovered that it is possible to use the twister 40 type of crystal element and at the same time keep the size of the device to a minimum.

The connecting means disclosed is compact and overcomes a source of difficulty with these devices that has been very annoying. In the past, difficulty has been had with the breakage of the connecting wires. With my device the ends 45 of the wires are protected and breakage is reduced to a minimum. Furthermore, disassembly of the wire connection from the device is conveniently and easily accomplished. At the same time the weight and size of the connection 50 has been kept to a minimum.

The elongated shell of the connecting device causes the force of a pull on the cord to be directed to the bottom of the ear piece with the result that pulling on the cord does not tend to pull 55 the ear piece out of the ear as would be the case if the force were applied near the center or top of the case.

The connecting means, consisting of the key-shaped slot members, is to be described in detail 60 and claimed in an application for patent to be filed by W. E. Schauers who invented the same.

I claim:

1. In a device of the class described, a diaphragm, a twister type crystal driving element 65 having a driving portion, resilient leg members

for mounting said driving element, one of said leg members being larger than any other leg, the leg of the largest area being positioned opposite the driving portion of said crystal element, stiffening means for said leg member of largest area, a diaphragm, and means for connecting the driving portion of said crystal element to said diaphragm.

2. In a device of the class described, a casing, a diaphragm mounted in said casing, a driving element for said diaphragm having a driving portion, said driving element being polygonal in shape and having a corner thereof substantially opposite said driving portion, means for connecting said unmounted corner to said diaphragm, mounting means for said driving element connected at other corners thereof, said mounting means consisting of leg members formed of resilient material and means for stiffening at least one of said mounting members at the outside edge thereof and at a point substantially opposite from the driving portion of said driving element.

3. In a device of the class described, a casing, a diaphragm mounted in said casing, a twister type crystal element for driving said diaphragm having four corners, one corner of said driving element being connected to said diaphragm to drive the same, means for mounting said crystal element, said means comprising a leg formed of resilient material opposite said corner connected to said diaphragm, stiffening means for a portion of said leg, and side legs of lesser area than said first mentioned leg mounted at the other corners of said crystal element.

4. In a device of the character described, a casing substantially circular in shape, a radial offset portion in said casing adapted to fit between the tragus portions of the ear, the back of said offset portion being flush with the major portion of the back of said casing, a diaphragm mounted in said casing, a twister type crystal driving element projecting into the offset portion in said casing and having the driving portion thereof opposite said diaphragm, means for connecting said diaphragm to the driving portion of said crystal element, and means for supporting said crystal element in said casing.

5. In a device of the character described, a substantially circular shaped casing, a radial offset portion in said casing adapted to fit against the tragus portions of the ear, the back of said offset portion being flush with the back of the major portion of said casing, a diaphragm mounted in said casing, a twister type crystal driving element projecting into the offset portion

in said casing and having the driving portion thereof beneath said diaphragm, means for connecting said diaphragm to said driving portion of said crystal element, means for supporting said crystal element in said casing, said supporting means consisting of legs having a relatively slow resiliency response and a stiffening member engaging said crystal element and passing over at least one edge of one of said leg members.

6. In a device of the class described, a casing, a diaphragm mounted in said casing, a twister type crystal element connected adjacent its front end to said diaphragm for driving the same, means for supporting said element in said casing, said supporting means consisting of legs having a relatively slow resiliency response, said legs comprising side legs and a rear leg, said side legs being of substantially less area than said rear leg, and means for stiffening said rear leg.

7. In a device of the class described, a casing, a diaphragm mounted in said casing, a twister type crystal element connected to said diaphragm for driving the same, means for supporting said element in said casing, said supporting means consisting of side legs and a back leg having a relatively slow resiliency response, said legs being in substantially the following proportion in relation to said crystal driving member, said legs being approximately $\frac{1}{8}$ of an inch thick, said side legs being approximately $\frac{1}{8}$ of an inch square and said rear leg being approximately $\frac{3}{8}$ of an inch square.

8. A device of the class described, a casing, a twister type of crystal element mounted in said casing, means for supporting said crystal type driving element having substantially the same resiliency characteristics as a highly plasticized cellulose nitrate plastic having a relatively slow response, said means comprising a leg mounted at one end of said crystal and legs mounted at the sides of said crystal, the area of said end being slightly in excess of twice the area of one of said side legs.

9. A device of the class described, a casing substantially circular in shape and provided with a hollow radially projecting portion adapted to fit between the tragus portions of the ear, said casing having a depressed portion opposite the projecting portion, connecting means mounted in said depressed portion, a twister type crystal driving element having a portion thereof mounted in the projecting portion of said case and the driving portion thereof at substantially the center of said case.
